UNITED STATES PATENT OFFICE.

AUGUST DEŽELA, OF VANCOUVER ISLAND, BRITISH COLUMBIA, CANADA.

FIBER SAVER.

1,423,199.

Specification of Letters Patent. Patented July 18, 1922.

Application filed November 12, 1920. Serial No. 423,589.

To all whom it may concern:

Be it known that I, AUGUST DEŽELA, a subject of the Kingdom of Serbs, Croates, and Slovenes, residing at Vancouver Island, 5 in the Province of British Columbia and Dominion of Canada, have invented certain new and useful Improvements in a Fiber Saver, of which the following is a specification.

10 This invention relates to improvements in paper manufacture and more particularly to the pulp treating means.

An important object of this invention is to provide a pulp saver for use in pulp and 15 paper mills having novel means whereby the pulp contained in the waste liquor from the blow pits or blow tanks and white water may be regained.

20 A further object of the invention is to provide a pulp saver having novel means whereby the heavy solid materials such as sand and mineral particles may be separated from the pulp or cellulose contained in the liquid discharged from the blow pits.

A further object of the invention is to provide a pulp saver which operates with a minimum of attendant labor and which requires but a small amount of power.

The invention forming the subject matter of this application aims also to provide a pulp saver which is simple to operate, efficient in use and cheap to manufacture.

Other objects and advantages of the invention will be apparent during the course of the following description.

In the accompanying drawings forming a part of this application, and in which like numerals are employed to designate like parts throughout the same,

Figure 1 is a plan view of the improved pulp saver,

Figure 2 is a longitudinal sectional view through the same,

Figure 3 is a detail view of the pulp saver,

Figure 4 is an enlarged fragmentary plan view of the improved pulp saver,

Figure 5 is an enlarged central vertical sectional view through the same,

Figure 6 is a fragmentary end elevation of the pulp saver.

In the drawings wherein for the purpose of illustration is shown a preferred embodiment of the invention, the numeral 10 generally designates the improved pulp saver having a trough 12 which receives the liquid discharged from the blow pits or blow tanks

of the mill. As illustrated in Figure 1, the trough 12 discharges the liquid which bears a quantity of pulp into a series of sediment collecting tanks 14 having downwardly extending baffles 16 which collect the scum in the liquid and prevent the scum from passing over the partitions 18. Upon entering the sediment collecting compartments 14, any solid particles such as sand, mineral 60 particles, or crumbled fire brick which may be in the discharge liquid, settle to the bottom of the compartment and may be periodically removed through openings 20. The openings, however, may be closed by vertically slidable gates 22. Sliding screens 24 may also be detachably extended over the opening 20.

Upon leaving the sediment collecting compartments 14 the liquid passes over the partitions 18 which terminate below the upper sides of the tank and enters a plurality of pulp receiving compartments 26. Before discharging, sliding gates are opened and waste liquor drained off through the screens, 75 compartments are then partly filled with water in order to obtain a proper dilution of settled pulp which is then washed out and pumped to the pulp storage.

As illustrated in Figure 5, a transversely 85 extending and transversely inclined baffle 28 is extended across each compartment above each partition 18 and serves to direct the inflowing liquid downwardly in the direction of the bottom walls of the pulp collecting 90 compartments 26. In thus directing the liquid downwardly upon entering the compartments the buoyancy of the pulp contained in the liquid is overcome so that the pulp will immediately begin to settle and 95 will not float upon the liquid. As the liquid flows through the tanks 26 the same approaches a transversely extending partition 30 which terminates below the top of the tanks 26 and serves to provide the tanks 26 100 from a discharge gutter 32. After depositing the pulp in the several compartments 26, the liquid enters the compartments or gutters 32 and passes off through openings 36. Any solid matter which may enter the 105 gutters 32 is retained therein by means of screens 38. Sliding gates 40 are employed for closing the discharge passages 36 when desired.

The pulp deposited in the several tanks 110 26 may be periodically discharged through a pipe 42 having a plurality of branches 44

extending into the several compartments 26. The branch pipes 44 are provided with covers 46 which may be simultaneously opened by means of operating members 48.

5 In the practice of the invention, the improved pulp saver will effect a saving of between 3 and 3½% of the daily pulp production of the mill. As the depth of the pulp deposited in the compartments 26 increases the velocity of the liquid increases proportionately. A centrifugal pump may be connected to the pipe 42 when it is desired to draw off the sediment or pulp collected in the several compartments 26.

10 15 Having thus described the invention, what is claimed is:

1. A pulp saver comprising a tank having inlet means, a partition arranged within the tank and dividing the same into sediment and pulp receiving compartments, and a transversely inclined baffle arranged in said pulp collecting compartment adjacent said partition and adapted for directing the inflowing liquid downwardly.

20 25 2. A pulp saver comprising a tank, a partition arranged therein thereby dividing the same into sediment collecting and pulp collecting compartments, a transversely inclined baffle secured above said partition and

adapted for directing the inflowing liquid 30 downwardly, a second partition arranged in said tank and forming a discharge gutter, said first and second named partitions terminating below the top of said tank.

3. A pulp saver comprising a tank having 35 an inlet spout, a partition arranged within the tank and dividing the same into sediment and pulp collecting compartments, discharge means for said sediment collecting compartment, a baffle traversing said sediment collecting compartment in spaced relation to said partition and terminating below the upper side of the tank, a second baffle traversing said pulp collecting compartment and being inclined transversely for 40 directing the inflowing liquid downwardly whereby the buoyancy of the pulp contained in the liquid is overcome, discharge means connected to said pulp collecting compartment, and a second partition arranged in 45 said tank and forming a discharge gutter.

In testimony whereof I have affixed my signature in the presence of two witnesses.

AUGUST DEŽELA.
